FINGER RING

Ernest Burk, Washington, D. C.

Application February 18, 1946, Serial No. 648,225

9 Claims. (Cl. 63—15)

1

This invention relates to finger rings and more particularly to a ring having a reversible setting support.

In finger rings of this type heretofore proposed, the setting support is either detached from the ring shank, inverted and then attached to the ring shank to display the opposite face of the setting support, or the setting support is pivoted to the ring shank so that it may be rotated to show either of its faces, the finger of the wearer or a spring latch being relied upon to maintain the desired face in position.

Each of these arrangements has a number of disadvantages, the chief of which are complexity of construction with resultant initial expense and high maintenance cost because of the fragile parts. The complex construction also reduces the ease with which the setting support can be reversed and thus limits the usefulness of the ring.

To avoid these disadvantages, a finger ring having a reversible setting support has been devised wherein the setting support is pivotally mounted in a gap in an incomplete circular ring shank, the gap being normally smaller than the setting support so that the ring shank becomes stressed when the setting support is placed therein whereby the setting support is tightly gripped by the ring shank. To maintain the setting support immovable with respect to the ring shank when the setting support is in one of its desired positions, the ring shank is provided with detents which snap into grooves in the setting support when the detents are in alignment with said grooves.

To reverse the setting support and expose its opposite face, it is only necessary to spread the ring shank slightly so that the detents will disengage the grooves whereupon the setting support may be easily rotated on its pivots until the detents again snap into the grooves at which time the opposite face of the setting support becomes visible. It is apparent that with this construction, it is unnecessary to dismantle any of the parts to produce a reversal thereof nor is it necessary to rely on the finger of the wearer or additional spring catches to hold the parts in their proper relative positions.

One of the objects of the present invention is the provision of a new and improved finger ring possessing all of the advantages of arrangements heretofore proposed for this purpose and in which the foregoing disadvantages have been eliminated.

Another object of the invention is to provide

2

an arrangement of the character disclosed in which a flexible ring shank is employed for gripping a reversible setting support thereby eliminating the use of spring catches.

5 A further object of the present invention is the provision in a reversible ring of a detent arrangement which cooperates with a flexible ring shank and a reversible setting support to maintain the setting support in any one of its desired positions.

10 Another of the objects of the present invention resides in the provision of a setting support gripped in a prestressed ring shank and pivots extending between the support and the shank to permit inversion of the support with respect to the shank.

15 Still other objects, advantages, and improvements will become apparent from the following detailed description of the invention taken in connection with the accompanying drawing in which:

Fig. 1 is a side view of the inventive finger ring partly broken away and showing the pivoted setting support rotated from its normal position;

Fig. 2 is a plan view partly broken away of the 20 ring with its parts in the position illustrated in Fig. 1;

Fig. 3 is a plan view of the ring with parts 25 broken away showing the setting support in its normal position;

Fig. 4 is a side view of the ring taken on the line 4—4 of Fig. 3;

Fig. 5 is a plan view of the setting support when detached from the ring shank;

Fig. 6 is a partial view similar to Fig. 4 of a 30 modification; and

Fig. 7 is a plan view of the setting support employed in the modification of Fig. 6.

Referring now to the drawings in which like numerals of reference are employed to designate like parts throughout the several views, there is shown in Fig. 1 a complete finger ring according to a preferred embodiment of the invention and indicated generally by the numeral 10.

40 The ring 10 comprises a flexible substantially circular shank 11 having a gap therein provided with two opposing faces 12 and 13. Mounted in said gap on pivot pins 14 and 15 projecting from the faces 12 and 13 respectively is a setting support 16 which is provided with apertures 17 and 18 to receive the pins 14 and 15, respectively. The setting support 16 is wider than the gap in the shank 11 so that the gap must be expanded and the shank 11 placed under stress when the setting support is mounted on its pivots within 45 the gap. The pivot pins are axially slidable in

the apertures 17 and 18 to permit expansion of shank 11.

The shank faces 12 and 13 are provided with elongated projecting detents 19 and 20, respectively, which are made integral with the shank 11 and are shaped to enter grooves 21 and 22, respectively, in the setting support 16 and snugly interfit therewith. The side surfaces of the detents 19 and 20 converge slightly from the faces 12 and 13 for a purpose to be made apparent hereinafter.

The setting support 16 has provided on its opposite faces insignia 23 and 24, respectively, which may comprise engraved or intaglio signets, emblems or jewelled settings, each face having a different aspect as indicated in Figs. 1 and 3, respectively.

The operation of the arrangement is as follows:

When it is desired to change the insignia, emblem or jewelled setting that being worn to that of the opposite face of the setting support, it is necessary only to disengage the setting support 16 from the ring shank 11 by springing the ring shank sufficiently to permit the detents 19 and 20 to be withdrawn from the grooves 21 and 22 whereupon the setting support may be rotated from its prior position (see Fig. 3) to its new position as indicated in Fig. 1.

The springing of the ring shank 11 may be accomplished in one of two ways. First, the ring shank may be forcibly spread by grasping both sides of the shank and pulling in opposite directions until the detents 19 and 20 emerge from the grooves 21 and 22 sufficiently to permit initiation of the rotation of the setting support 16 whereupon a slight displacement of the detents with respect to the grooves will maintain the sprung condition of the ring shank 11 until the setting support has been rotated 180 degrees from its initial position when the detents will again be permitted to snap into the grooves.

The second manner in which the ring shank 11 may be sprung is made possible by reason of the aforementioned convergence of the side surfaces of the detents 19 and 20 to cause the detents to operate as cams with respect to the snugly fitting grooves 21 and 22 when the setting support 16 is grasped between the fingers and forced to rotate with respect to the ring shank 11. Upon initial rotation of the setting support, the sloped surfaces of the grooves operate upon the sloped surfaces of the detents to force the detents to leave the grooves thereby simultaneously springing the ring shank 11. When the setting support has been rotated 180 degrees, the stress in the ring shank will cause the detents to again snap into the grooves whereby the setting support will be rigidly maintained in its reversed position with respect to the ring shank. During the springing of the ring shank 11, the pivot pins 14 and 15 move axially in their respective apertures 17 and 18 as can be seen by a comparison of Figs. 1 and 3.

Numerous modifications in the arrangement will immediately suggest themselves. For example, the positions of the detents and their co-operating grooves may be reversed so that the detents project from the setting support and the grooves are cut in the ring shank faces 12 and 13, the operation remaining substantially the same.

The positions of the pivot pins and their co-operating apertures may also be reversed and this arrangement is shown in Figs. 6 and 7 in which like numerals bearing the subscript *a* as are used in Figs. 1 to 5 are employed to denote similar parts.

It will be noted, in Figs. 6 and 7, that the pins 14*a* and 15*a* are affixed to the setting support 16*a* and that the cooperating apertures 17*a* and 18*a* are bored in the ring shank 11*a*. The apertures 5 may be bored completely through the ring shank and may then be partly filled with metallic plugs as shown at 25 or the apertures may be bored partly through the shank faces while the ring shank 11*a* is a flat blank and before it has been given its ring shape.

The operation of the modification of Figs. 6 and 7 is in all respects similar to that of the embodiment of Figs. 1 to 5, as stressing of the ring shank in either of the two ways described above will 15 permit rotation of the setting support 16*a* with respect thereto.

Although, in accordance with the provisions of the patent statutes, this invention has been disclosed in concrete form with reference to a preferred embodiment and a single modification thereof, it will be understood that these forms are merely illustrative and that the invention is not limited thereto since alterations and modifications will readily suggest themselves to persons 25 skilled in the art without departing from the true spirit of this invention or the scope of the annexed claims.

What is claimed as new and desired to be secured by Letters Patent of the United States is:

30 1. A finger ring comprising a reversible setting support disposable in either of two positions, a prestressed shank for gripping said setting support, said setting support being pivotally mounted on said shank, and means comprising a detent 35 and a cooperating groove for locking said setting support in either of said two positions.

2. A finger ring comprising a reversible setting support disposable in either of two positions, a prestressed shank for gripping said setting support, said setting support being pivotally mounted on said shank, and means comprising a detent 40 and a cooperating groove on said setting support for locking said setting support in either of said two positions.

45 3. A finger ring comprising a reversible setting support disposable in either of two positions, a prestressed shank for gripping said setting support, said setting support being pivotally mounted on said shank, and means comprising a plurality 50 of detents on said shank and cooperating grooves on said setting support for locking said setting support in either of said two positions.

4. A finger ring comprising a support bearing 55 emblems on its opposite faces, a prestressed shank for gripping said support, means extending between said support and said shank around which said support is adapted to pivot, and means for locking said support to said shank comprising 60 a detent on said shank and a cooperating groove on said support.

5. A finger ring comprising a setting support, a prestressed shank for gripping said setting support, a pair of pivots extending from opposite 65 sides of said shank, a pair of opposed apertures in said setting support for receiving said pivots, and means for locking said setting support to said shank comprising a detent on said shank and a cooperating groove in said setting support.

70 6. A finger ring comprising a setting support, a prestressed shank for gripping said setting support, a pair of pivots extending from opposite sides of said setting support, a pair of opposed apertures in said shank for receiving said pivots, 75 and means for locking said setting support to said

shank comprising a detent on said shank and a cooperating groove in said setting support.

7. A finger ring comprising an incomplete flexible ring member having a gap therein, a setting support larger than the gap pivoted therein and gripped by the stressed ring member, and means for locking said setting support to the ring member comprising a detent on the ring member and a cooperating groove in said setting support.

8. A finger ring comprising an incomplete flexible ring member having a gap therein, a setting support larger than the gap pivoted therein and gripped by the stressed ring member, and means for locking said setting support to the ring member comprising a cam-shaped detent on the ring member and a cooperating groove in said setting support.

9. A finger ring comprising an incomplete flexible ring member having a gap therein, a setting supporting member larger than the gap mounted therein and gripped by the stressed ring member, pivots extending between the two

members for permitting rotation therebetween, and means for locking said setting supporting member to the ring member comprising a cam-shaped detent coaxially arranged with respect to one of the pivots and mounted on one of said members and a cooperating groove in the other of said members.
